Benz' B. Moore

UNITED STATES PATENT OFFICE.

BENJAMIN B. MOORE, OF DETROIT, MICHIGAN.

HYDRANT.

Specification of Letters Patent No. 33,095, dated August 20, 1861.

To all whom it may concern:

Be it known that I, BENJN. B. MOORE, of the city of Detroit, in the county of Wayne and State of Michigan, have invented a new and Improved Fire-Reservoir and Cistern Valve; and I do hereby declare that the following is a full and exact description thereof, reference being had to the accompanying drawings, and the letters of reference marked 10 thereon, in which—

Figure 1 is a side elevation and Fig. 2 is a central vertical section.

To enable others to make and use my invention I will proceed to describe its construction and operation.

I construct a pipe of metal of any required size and form as represented in the drawing by the letters A, A, Fig. 2 having a cap or cover B, with a valve seat K, attached thereto, and bolted to the upper ends of the pipe A A. On this cap is attached a bracket in the form of a tripod as shown at f, in the upper end of which is placed a nut, g, through which a screw on the lower end of valve rod E, passes. The valve rod E, is connected to the valve stem d, by means of a thimble h, which is made in two halves, having projections on their inner surfaces at top and bottom and held in their proper position 20 when ready for use by a permanent metal band i. When it is required to disconnect the valve rod E, and the valve stem d, the metal band i is slipped off from the thimble h, which being made in two halves is easily 25 removed.

On the lower end of the valve rod E, and the upper end of valve stem d, are collars

or flanges represented in the drawings by j j their diameters nearly corresponding with the largest inside diameter of the thimble. 40 When it is desired to connect the rod and stem the lower end of the valve rod E, and upper end of valve stem d, are brought together, the thimble h is then put in its place with the metal band on the outside 45 holding the two halves firmly together, the projections on the inside of the thimble fitting over the collars on the valve rod and valve stem loosely so that either may have a rotating motion without turning the other. 50 On the lower end of the valve stem d, is a valve e, which is made to correspond and fit the valve seat K attached to the cap B. When it is required to take this machine apart, all that is necessary is to slip the band 55 i up from the thimble which being made in two halves is easily removed, and taking off the cap B by removing the bolts b b. The operation of the valve is produced by turning the valve rod E, which is raised or 60 lowered by means of the screw on its lower end.

The valve as represented by Fig. 2 is entirely open.

What I claim as my invention and desire 65 to secure by Letters Patent is—

The combination of the cap B with valve seat attached, bracket f, nut g, thimble h, and band i for the purposes herein set forth.

BENJN. B. MOORE.
